UNITED STATES PATENT OFFICE.

WILLIAM G. SCHOLOSKE, OF BALTIMORE, MARYLAND.

AUTOMATIC TRAIN-STOP.

1,135,467.

Specification of Letters Patent. Patented Apr. 13, 1915.

Application filed April 15, 1914. Serial No. 832,02

To all whom it may concern:

Be it known that I, WILLIAM G. SCHOLOSKE, a citizen of the United States, residing in the city of Baltimore and State of Maryland, have invented certain new and useful Improvements in Automatic Train-Stops, of which the following is a specification.

This invention relates to automatic train stops and the primary object of the invention is the provision of mechanism for attachment to the forward end of a locomotive, for automatically stopping the travel of the locomotive when a danger signal has been passed, by the bleeding of the air brake system of the locomotive and train attached thereto, whereby the train will be stopped for the prevention of accidents contingent with inattention to or improper construing 20 of orders or signals by the trainmen.

Another object of this invention is the provision of means for mounting the air system bleeding mechanism upon the forward end of the locomotive in yieldable relation thereto whereby the swaying of the train or engine in transit, the rounding of curves or bends will not affect the positioning of the mechanism and also to provide means arranged along side the track upon 30 which the train travels for automatically actuating said air valve bleeding mechanism when desired.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts throughout the several views, and in which:—

Figure 1 is a view of the front end of a locomotive showing the improved mechanism for automatically stopping the same, applied thereto, and in side elevation. Fig. 2 is a top plan view of the mechanism for 45 automatically bleeding the air brake system for stopping the train. Fig. 3 is a fragmentary view in bottom plan, showing parts broken away, of the air bleeding mechanism, Fig. 4 is a cross sectional view on the line 50 4—4 of Fig. 2. Fig. 5 is a fragmentary

view in side elevation of a part of the air system bleeding mechanism.

Referring more particularly to the drawings 1 designates a locomotive of any ordinary type of construction, such as is employed for the propulsion of trains over railways, and which has a pilot 2 formed thereupon, to which pilot is attached supporting bars 3, the bars 3 are bent upwardly and outwardly and have the block 4 rigidly mounted upon their outer terminal ends. The block 4 has a slot or groove 5 extending diagonally across its upper face, which groove has a constricted mouth as is clearly shown in Fig. 4 of the drawings, and it 60 forms a guideway for the projection 7 which is formed upon the under surface of a plate 8, the projection being slidably seated in the groove 5.

The block 4 has bolts 9 and 10 carried thereby, which bolts extend upwardly from the upper face of the block and are slidably seated in slots 11 and 12, which slots are formed diagonally within the plate 8 parallel with the longitudinal lines of the projection 7 which is formed upon the base of the plate and they limit the sliding movement of the plate upon the block 4 by engaging the terminal ends of respective slots in which they are slidably positioned. The 75 plate 8 has a valve seat 15 formed upon the edge of the same which projects transversely from the engine 1 and the valve seat 15 has communication through flexible pipes 16 and 17 to the air brake controlling system 80 of the engine, the pipe 17 of which has egress into space for bleeding the air from the system for applying the brakes and stopping the train when the valve 18 which is positioned within the valve seat 15 is 85 operated for opening the passage way between the pipes 16 and 17.

The valve 18 is rotatably seated within the valve seat 15 and it has an opening extending transversely and diametrically 90 therethrough, which opening has communication with the interior bores of the pipes 16 and 17. The valve 18 has a valve stem 19, which valve stem is triangular shaped in cross section, protruding beyond the upper end of the valve casing 15 and the triangular shaped valve stem 19 has a finger 105 20 removably mounted thereupon, which finger extends outwardly from the engine 1 and is positioned for contact with a signal 110

21, which signal is placed along side the track upon which the train travels, and is operable for proper positioning to indicate that the track is clear or safe, or that it is blocked and that the train must not pass thereupon. The signal 21 constitutes or embodies a rod which extends vertically from the ground and has a roller 22 mounted adjacent its upper terminal end, which 10 roller is positioned for contact with the finger 20 when the track is closed.

A guarding guide 25 is positioned above the valve 18 and valve seat 15, and it is connected to the plate 8 by a plate 26 and bolts 15 27, which bolts extend through the plate 26 and into the plate 8. The guarding guide 25 has a forwardly projecting finger 28 which has its outer edge curved as at 29, for providing a guide to insure the proper striking 20 of the finger 20 with the signal 21 and it is positioned above the valve for forming a protecting guard therefor as well as for facilitating the holding of the finger 20 against vertical movement.

25 The finger 20 has a depending lug 30 formed upon its inner end adjacent the enlarged portion 31, which enlarged portion is mounted about the rectangular valve stem 19, and the lug 30 travels in a guide-way 32 formed on the upper surface of the valve seat 15 and about the central axis of the valve stem 19, as an axis thereof, being limited in its travel by the shoulder 33 formed at one termination of the guide-way 35 32 and by the lug 34 formed at the other termination of the guide-way and extending outwardly from the raised portion 35 of the valve seat 15 as is clearly shown in Fig. 2 of the drawings. The lug 30 traveling in the 10 guide-way 32 and being limited by the shoulder 33 and the lug 34 regulates the rotation of the valve 18 within the valve seat and insures of the proper positioning of the same.

45 The block 4 has a screw threaded opening 37 extending thereinto from the side or edge which faces the locomotive 1, parallel with the groove 5 which is formed in the upper face of the block and positioned directly beneath the center of the groove. The opening 37 has a bolt 38 detachably seated therein, which bolt has a washer 39 mounted upon its outer end abutting the inner side of the head of the bolt. A spiral spring 40 is 50 coiled about the bolt 38 and one end thereof engages the washer 39 while the other end engages one side of a plate 41, which plate is detachably connected to the plate 8 in any suitable manner such as by bolts 42, or other 55 60 suitable fastening means. The plate 41 has an opening 43 extending therethrough, in which opening the bolt 38 is slidably seated. The spring 40 is provided for the purpose

of permitting of resilient lateral movement of the plate 8 and the various mechanism carried thereby, to compensate for the swaying of the locomotive or the rounding of a curve and to permit of a give or yielding movement of the plate when the finger 20 contacts with the signal to prevent the 70 breaking or disruption of the attachment of the various parts to the plate 8.

In the operation of the improved automatic train stop; when the signal 21 is set to designate that the track is closed, the 75 finger 20 will, upon approach of the train to the signal be engaged by the roller 22 and forced rearwardly as is indicated by the arrow A in Fig. 2, and this swinging or pivotal movement of the finger will operate the 80 valve 18 causing the opening therein to be positioned so that communication between the pipes 16 and 17 will be open, whereby the air system for controlling the brakes of the train will be bled, causing the train to come to a stop, almost immediately and thereby eliminating the possibility of accidents such as would occur by the passing of the train upon a blocked section of track.

From the foregoing description taken in 90 connection in the accompanying drawings the advantages of the construction and of the method of operation of the improved automatic train stop will be readily apparent to those skilled in the art to which this 95 invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

100 What is claimed is:

In an automatic train stop, the combination with a train embodying a prime mover, and an air brake system for said train, of a plate yieldable horizontally carried by said prime mover forwardly and to one side thereof, a valve supported by said plate and interposed in said air brake system, a finger operatively connected to said valve and normally extending laterally of said prime 110 115 mover, a guarding guide carried by said plate and positioned above said valve; and means for operating said finger for operating said valve for bleeding said air system.

In testimony whereof I affix my signature 120 in presence of two witnesses.

WILLIAM G. SCHOLOSKE
